Attorney.*

UNITED STATES PATENT OFFICE.

ANDREW SAMBORSKY, OF ST. LOUIS, MISSOURI.

GUARD FOR ELECTRIC SWITCHES.

Application filed May 5, 1921. Serial No. 466,934.

To all whom it may concern:

Be it known that I, ANDREW SAMBORSKY, a citizen of the United States, residing at St. Louis, State of Missouri, have invented 5 certain new and useful Improvements in Guards for Electric Switches, of which the following is a specification.

My invention has relation to improvements in guards for electric switches, and 10 consists in the novel details of construction more fully set forth in the specification and pointed out in the claims.

The object of the present invention is to provide a guard that will completely house 15 the switch, the handle being the only part exposed and that operable through the guard housing. A further object is to so completely enclose the line wires leading to the switch that it will be impossible to tap 20 the same and steal electricity. Further objects are to provide a guard that may be applied to existing switches without modifying their construction; one that is simple; one that eliminates the danger of fires from 25 arcing of the switch; and one possessing further and other advantages better apparent from a detailed description of the invention in connection with the accompanying drawings in which—

Figure 1 is a top plan of the guard with parts broken away; Fig. 2 is a front elevation of the same with parts broken away; Fig. 3 is a side elevation; Fig. 4 is a horizontal cross-section of the front of the guard 30 taken on the line 4—4 of Fig. 2; Fig. 5 is a view looking at the inside of the housing; Fig. 6 is a front elevation of the switch with the housing removed; Fig. 7 is a vertical longitudinal section on the line 7—7 of Fig. 40 2; Fig. 8 is a face view of the shutter through which the switch handle operates, the shutter plates being disposed for a raised position of the switch handle; and Fig. 9 is a view similar to Fig. 8 with the shutter 45 plates disposed for a lowered position of the switch handle.

Referring to the drawings, 1 represents a switch block or board having a knife switch 2 mounted thereon, the line wires a, a' leading 50 to contacts 3, 3' and wires b, b' leading to contacts 4, 4'. The switch has a handle 5 secured to the cross-piece 6, and is mounted on an insulating block 7 secured to the

switch board 1 by screws 9. The parts thus far described are old and well understood 55 in the art.

In order that one may not be shocked by touching the switch members I provide a guard entirely enclosing the switch, said guard comprising a pair of securing walls 60 10, 10' provided with base portions 11, 11' which are slipped under the block 7 after which the screws 9 are screwed down tightly to hold the walls 10 in place. A housing 12 having an elongated opening O to receive the 65 switch handle 5 and an insulating lining 13, is placed over the switch, the side walls c, c' of the housing coming inside the securing walls 10, 10', and the housing is anchored to the securing walls by a bolt 14 which 70 passes through the securing walls 10 and side walls and lining of the housing, the bolt having a wing nut 15 passed over its threaded end to secure the parts in place. In order that the housing 12 may not be removed without it being known a seal is provided comprising a wire 16 passed through 75 a hole in the bolt 14 and wing nut 15, and also passed through an opening in an ear 17 in one of the securing walls 10. The ends 80 of the seal are soldered into a slug 18. Since the walls 10 are clamped beneath the block 7 and the housing is fixed to the walls 10 it is impossible to remove the housing without first removing the bolt 14 and breaking 85 the seal.

The opening O of the housing must needs be of considerable length to allow for the throw of the switch handle 5 in opening and closing the switch, consequently some means 90 must be provided for closing this opening and keeping it closed while the switch handle is being moved. This is done as follows: Operating in grooves 19 between the lining 13 and front wall of the housing are 95 a series of overlapping plates 20, 21, 22, 23, provided with openings o, o', o'', o''' progressively decreasing in size, the opening o''' in the inside plate 23 being just large enough to receive the switch handle 5. The 100 edges of the plates 20 and 21 are flanged over to maintain the plates in nesting relation. As the switch handle 5 is pulled down it will move the plate 23 with it until the handle strikes the edge o'' when the 105 plate 22 will also be moved downwardly as

will likewise the plates 21 and so with a continued movement of the handle until the switch is wide open. In closing the switch the same operation will take place upwardly. The position of the plates when the switch is closed is shown in Fig. 8, and when it is open is shown in Fig. 9. The object of having a plurality of plates, arranged to telescope, as it were, is to permit of a greater switch throw in shorter limits of shutter movement.

The housing is provided with notches *n* to permit the wires to enter, and in order to close these notch openings strips 24 and 25 are disposed between the edges of the lining 13 and the housing wall, the former being recessed at *r* to receive the end tongues 20', 21', 22', 23' of the plates 20, 21, 22, 23. Strips 26 and 27 are disposed just inside the strips 24 and 25 respectively in grooves *m*, *m*, and *m'*, *m'* in the lining walls. The strips 24 and 26 have oppositely disposed notches *n'*, *n''* respectively to receive wires *a*, *a* and confine them (Fig. 1) while the strips 25 and 27 have oppositely disposed notches *p*, *p'* respectively to receive wires *b*, *b* and confine them (Fig. 7). Thus the openings where the wires enter the housing are closed so as to prevent the insertion of

conductors to the switch for the purpose of 30 stealing electricity.

Having described my invention, I claim:

1. In combination with a switch board and an electric switch mounted thereon, a switch guard adapted to be positioned over the switch and enclose the same, means for securing the housing to the switch board, one wall of the housing having an opening through which the switch handle is freely operable, a series of plates operable by the switch handle in intimate relation with said wall of the housing, said plates being provided with openings successively decreasing in size so as to permit a given switch throw within narrow limits of the combined plate 40 movement.

2. A switch guard comprising a housing enclosing the switch, the switch handle operating through an opening in the housing, and a series of overlapping plates positioned over said opening, said plates having sliding movement relative to one another to maintain said opening closed during movement of the switch handle.

In testimony whereof I hereunto affix my 50 signature.

ANDREW SAMBORSKY.
